METHOD OF AND APPARATUS FOR CONTROLLING THE COMBUSTION OF OIL IN OIL BURNERS

Application filed July 12, 1921. Serial No. 484,141.

This invention relates to a method and apparatus for controlling the combustion of oil in oil burners. The invention will be hereinafter described, by way of example, 5 as applied to a field boiler of the type for drilling oil wells.

In the use of oil burners for commercial purposes, as for example, in boilers, it is customary to maintain from 30 to 60 pounds 10 pressure per square inch on the oil burner header and to vary the rate of feed of the oil to the burner by adjustment of the burner regulating valve.

Oil feeding systems have, however, been 15 devised in which the regulation of the feed of the oil is obtained by varying the pressure of the oil at the oil burner header from about 30 pounds to about 60 pounds per square inch. In certain of the last-mentioned systems the variations in the pressure 20 of the oil and, consequently, in the rate of feed of the oil, are accomplished automatically. In both the hand-controlled and automatic systems in which the rate of feed of 25 the oil is regulated by changing the pressure on the oil, a control valve is usually provided at each oil burner for manually modifying the pressure regulation. The pressure 30 of oil as it issues from a burner is, of course, the same as that surrounding the burner, and the pressure prevailing about a burner is 35 ordinarily atmospheric or slightly below atmospheric. The drop in pressure due to oil passing through the oil burner itself is usually 40 very small. The greater part of the drop in pressure from an amount varying between 30 and 60 pounds to atmospheric is effected at the regulating valve.

As a consequence of the high pressure on 45 the oil at the regulating valves of oil burners, the valve openings under normal conditions of operation are small. Even in the case of a burner of large capacity in which the regulating valve presents a relatively large opening 50 when the burner is being operated at its maximum rate, the opening becomes small at the lower rates of combustion as the fire is turned down. By reason of the small size of its opening, the burner regulating valve obstructs the movement through it of the for-

55 eign solid matter usually present in fuel oil, with the result that such matter accumulates on the supply side of the valve and seriously interferes with the flow of oil to the burner.

High pressure oil feeding systems are rendered 60 still more objectionable and unreliable by the fact that the small opening which regulates the feed of the oil is not circular or of other form presenting substantially equal dimensions. On the contrary, the opening 65 presented by the valve when adjusted for relatively low rates of flow is elongated and narrow as in the case of the usual globe valve or needle valve. In this position of adjustment the valve acts as a strainer, stopping 70 all foreign matter that cannot pass through the narrow slit.

75 Inasmuch as the rate of flow of oil through an opening carries directly as its area and the area of the opening varies substantially as the square of what may be denominated its mean dimension, assuming that the length and breadth of the area are simultaneously increased or decreased, it follows that valves 80 presenting small openings are very sensitive, it being understood that an equal change in its mean dimension will produce a much larger change in the area of a small opening than in that of a relatively large one. Accordingly, in the use of the present systems 85 of feeding oil, a minute adjustment of the regulating valve produces a large change in the rate of flow of oil to the burner. On this account it frequently happens in the use of oil-fired boilers that a small opening movement of the valve passes too much oil to the boiler and causes the stack of the boiler to smoke, and when the valve is turned toward closed position the flow of oil is shut off so 90 much that the fire-box is not properly filled with flame.

95 Perhaps the chief disadvantages, however, in the use of present systems of feeding oil to boilers is that when a correct adjustment is finally obtained it will continue for a short interval only. During this interval solid matter may accumulate at the valve and reduce the flow, or matter held back by the valve during the adjustment may work 100

through the valve opening and allow an excess of oil to flow to the boiler.

A further disadvantage of oil feeding systems as at present constructed is that by their use an operator can obtain almost unlimited combustion capacities with resultant damage to the heating appliance or to the process in which the heating appliance is being used. This source of trouble is aggravated by the necessity of making frequent adjustments of the regulating valve and the inability of the operator to determine the actual rate of oil flow.

A still further disadvantage in the use of present oil feeding systems is that since the actual rate of flow of oil to the oil burner can not be accurately controlled, it is impossible to regulate the ventilation of the burner so as to provide the amount of air needed for complete combustion of the oil without supplying a large excess of air.

It is an object of this invention to feed oil to a burner at a rate which can be readily and accurately determined and regulated.

25 A further object of the invention is to feed oil to a burner in a manner which will enable a desired rate of feed of the oil when once established to be retained unchanged without adjustment of the flow-regulating means.

30 A still further object of the invention is to control the ventilation of an oil burner so that at all rates of feed of oil, the amount of air admitted to the burner will be sufficient for complete combustion of the oil but will not be in any considerable excess over the amount required for complete combustion.

In the fulfillment of these objects in accordance with the invention, the flow of oil to the burner is controlled by a low pressure drop or differential across an orifice, and the rate of flow of oil to the burner is regulated by varying the pressure drop across the orifice between zero and a desired maximum. The pressure drop across the orifice in most installations is, preferably, limited to an amount not substantially exceeding one pound per square inch, and the orifice is made of relatively large size so that all foreign solid matter usually to be found in fuel oil may pass through it without obstruction. Preferably, the orifice is circular and the part which contains the orifice is so formed that the size of the orifice cannot be changed without substitution of parts, thereby obviating all danger of the size of the orifice being unduly restricted or increased by the operator.

60 In accordance with a further feature of the invention, the differential pressure across the orifice is controlled through the agency of a gaseous fluid, and the feeding of the oil is, preferably, accomplished in such a way that oil is fed to the burner only when there is a greater gaseous fluid pressure on the supply side of the orifice than on its delivery side.

65 Obviously, various gaseous fluids may be used

without departing from the principles of the invention, but when the invention is applied to steam boilers, it is preferable, for the sake of convenience, to utilize steam withdrawn from the boiler.

70 A further feature of the invention resides in simultaneously varying the rate of feed of oil to the burner and regulating the ventilation of the burner so that the amount of air admitted to the burner is always substantially that required for complete combustion of the oil. Various other features of the invention pertain to the utilization of steam or other gaseous fluid for varying and limiting the rate of feed of the oil, atomizing the oil, regulating the ventilation of the burner, and reducing the feed of oil to a boiler when the pressure of the steam in the boiler tends to exceed a pre-determined degree.

75 Still other objects and features of the invention will appear as the description proceeds and will be pointed out in the appended claims.

80 In the drawings which show a preferred embodiment of the invention:

Fig. 1 is a view in side elevation of an oil-fired boiler equipped with combustion controlling apparatus illustrative of the invention.

Fig. 2 is a view of the boiler in end elevation looking from the right in Fig. 1.

Fig. 3 is a sectional view in elevation of the device for regulating the feed of the oil.

Fig. 4 is a detail view of the orifice chamber.

Fig. 5 is a sectional elevation of the relief valve in the low pressure line for controlling the ventilation of the boiler and the feed of the oil to the boiler; and

Fig. 6 is a like view of the pressure regulator.

90 In the practice of the method of this invention for controlling the combustion of oil in oil burners, the oil is caused to flow through an orifice of relatively large size such as to enable all matter ordinarily present in fuel oil to pass freely through it, and a low pressure drop or differential usually less than one pound per square inch, which is approximately equivalent to 30 inches of oil, is utilized to produce flow of oil through the orifice to the burner. The size of the orifice in individual installations is preferably constant, and the control of the flow of oil to the burner is effected by varying the pressure differential across the orifice between zero and an amount which for most installations does not exceed one pound per square inch. A gaseous fluid is, preferably, employed to produce the pressure drop across the orifice, and the oil is caused to flow through the orifice under a head corresponding to the difference in gaseous fluid pressures on the oil supply side of the orifice and on its delivery side. The gaseous fluid may conveniently be used for atom-

izing the oil in the burner, and in such a case, the fluid is employed for controlling the feed of oil to the burner at a pressure less than the atomizing pressure.

The ventilation of the burner is also controlled by the pressure of the gaseous fluid in such a manner that the amount of air supplied to the burner will always be sufficient for the complete combustion of the oil without substantial excess. The rate of feed of oil to the burner is limited to a desired maximum by limiting the pressure differential across the orifice. This is in turn effected by subjecting the delivery side of the orifice to atmospheric pressure and limiting the pressure of the gaseous fluid on the oil at the supply side of the orifice. The gaseous fluid, preferably, controls the ventilation of the burner under a pressure substantially equal to the pressure imposed on the oil. Various kinds of gaseous fluids may be used without departing from the principles of the invention. In the application of the invention to steam boilers, however, the gaseous fluid pressure for regulating the feed of the oil and the ventilation of the burner is, preferably, obtained through the agency of steam withdrawn from the boiler. Moreover, when the invention is used in connection with steam boilers, the feed of oil to the boiler furnace is reduced whenever the pressure of the steam in the boiler tends to exceed a predetermined degree.

The apparatus shown in the accompanying drawings constitutes a convenient and satisfactory means whereby the method of this invention may be put into practice. It is recognized, however, that the method may be carried out by apparatus of varying forms. Accordingly, the apparatus herein disclosed is to be considered as illustrative only of means by which the method may be applied in a commercial way.

In the illustrated construction, a field boiler 10 of the type used for drilling oil wells is provided with a sub-furnace 12 in which is placed an oil burner 14. As shown, the oil burner 14 comprises a cylindrical chamber in which is fitted a core 16 having a single opening 18 for oil and a plurality of openings 20 below the opening 18 for conducting an atomizing fluid into close contact with the oil. The arrangement of the openings 20 is such as to form the atomizing fluid into a fan-like layer upon which the oil falls as it issues from the opening 18. The oil burner 14 does not require further description inasmuch as it is of a type well known to the trade and constitutes per se no part of the present invention.

Oil is conducted to the burner 14 by a pipe 22 which communicates with the burner substantially in line with the opening 18. The pipe 22 extends through the front wall of the sub-furnace 12 and is connected at its outer

end to a vertical pipe 24 which receives oil from a flow-regulating device 26. The device 26 is supplied with oil by a pipe 28 which contains a valve 29 and may also be provided with a strainer 30 to prevent the passage of large foreign objects of a kind not ordinarily present in fuel oil.

The flow-regulating device 26 comprises a member 32 provided with an orifice or restricted opening 34, and means for creating a low drop in pressure across the orifice to cause oil to flow through it to the burner 14. In the present exemplification of the invention, the pressure of a gaseous fluid is utilized to regulate the flow of oil through the orifice 34. Consequently, it is desirable, in order to cause the rate of flow of oil through the orifice to be influenced by the least possible number of variable factors and thereby enable the rate of flow of the oil to be regulated with the greatest possible accuracy, that the pressure on the oil as it enters the flow-controlling device 26 shall have no effect on the pressure at the orifice 34. Manifestly, if oil is supplied to the device 26 by a pump, the pressure on the oil as it enters the device will vary with the speed of the pump and the head of oil in the pipe 28, and if oil is supplied to the device 26 by gravity alone, the pressure on the oil will still vary in accordance with the level of the oil in the ultimate source of supply. To the end that the rate of flow of oil through the orifice 34 may be entirely unaffected by the pressure of the oil as it enters the device 26, the flow-controlling device includes a trap or chamber 36 located on the supply side of the orifice 34 and provided with means for maintaining the oil in the trap at a fixed level. As shown, such means comprises a valve 38 (Fig. 3) arranged to control the inflow of oil to the chamber 36 from the pipe 28 and connected by suitable linkage 40 to a float 42. The arrangement of these parts is such that when the oil tends to rise above the fixed level, the float 42 is raised and moves the valve 38 toward closed position, whereas when the oil tends to recede below the fixed level, the float 42 falls and moves the valve 38 toward open position.

The trap 36 is formed at one side near its bottom with a projecting portion 44 in which the lower end of an upwardly inclined pipe 46 is threaded. At its upper end the pipe 46 is screwed into a disc-shaped chamber 48 which will hereinafter, for convenience, be sometimes referred to as the orifice chamber. The orifice member 32 is mounted so that it communicates on its supply side with the pipe 46 and on its delivery side with the orifice chamber 48. As shown, the orifice member is in the form of a plate threaded into the orifice chamber 48 adjacent to the pipe 46, and the orifice 34 is of the type commonly called an "orifice in thin plate." It is evi-

dent that the orifice plate may if desired be mounted in the pipe 46 rather than in the orifice chamber 48. The pipe 24 is threaded into the bottom of the orifice chamber 48 and 5 conducts the oil from the orifice chamber to the oil burner pipe 22.

The oil as it issues from the orifice 34 is subjected to atmospheric pressure. To this end the orifice chamber 48 is provided at its 10 top with an opening 50. In this connection, it should also be noted that the burner 14 is of a type such that the introduction of an atomizing fluid into it produces no suction in the oil pipes 22 and 24. In order to insure 15 against the creation of any suction in the pipes 22 and 24 and the orifice chamber 48, the chamber 48 is formed at its sides with two large openings 52. The openings 52 are 20 preferably threaded to allow them to be closed by screw plugs 53 when necessary to prevent the entrance of dust into the chamber 48.

Inasmuch as the orifice chamber 48 is open to the atmosphere, the pressure on the delivery side of the orifice is substantially constant. Consequently, the rate of flow of oil 25 through the orifice 34 may be controlled by gaseous fluid pressure imposed on the oil in the trap 36. In order to enable a low pressure drop to be readily obtained across the orifice 34 and to enable the pressure drop to be readily reduced substantially to zero thus 30 substantially suspending the flow of oil to the burner 14, the oil in the trap 36 is preferably maintained at the level of the orifice 34. With this construction, oil is caused to 35 flow through the orifice only when there is a greater gaseous fluid pressure on the oil in the trap 36 than on the delivery side of the orifice 34, or, in other words, only when the 40 pressure of the gaseous fluid in the trap 36 is greater than atmospheric pressure. Consequently, if the gaseous fluid pressure in the trap 36 is reduced to atmospheric, the flow 45 of oil to the burner 14 through the orifice 34 is discontinued.

The use of a low pressure drop for producing flow of oil through the orifice 34 is of 50 particular importance in field boilers since it enables oil to be fed to a boiler from a field tank by gravity. The pipe 28 of the illustrated installation is designed to receive oil 55 from a field tank without the use of a pump. The expense and trouble which are avoided in this way are very considerable.

Means is preferably provided for enabling 60 a small quantity of oil to be supplied to the burner 14 at any time regardless of pressure conditions in the trap 36. A convenient embodiment of such means consists of a pilot pipe 54 interposed between the oil trap 36 and the pipe 22 and provided with a valve 55.

In the illustrated construction, the gaseous 65 fluid which controls the feed of the oil is conducted to the trap 36 from a stand-pipe

56 connected to the top of the trap by a pipe 58 (Fig. 2). A second pipe 60 leads from the trap 36 below the oil level to the stand-pipe 56. With this construction, it is evident that the oil level in the stand-pipe 56 will be the same as that in the trap 36. In order to enable the oil level to be observed by the operator, a gauge glass 62 is connected to the stand-pipe above and below the oil level by pipes 64 and 66 respectively. A second gauge 70 glass 68 communicates at its lower end with the stand-pipe 56 below the oil level and is open to the atmosphere at its upper end. The stand-pipe 56 may also be provided at its bottom with a pet-cock 70.

Since the gauge glass 68 and the orifice chamber 48 are both open to the atmosphere, the height of oil in the glass 68 indicates the pressure differential or drop across the orifice 34. The glass 68 is calibrated so as to enable 80 the pressure differential to be measured. In order to measure the rate of flow of oil directly, the gauge glass 68 must be calibrated to correspond with the size of the orifice 34. If, for any reason, the size of the orifice should 90 be changed, a new gauge glass 68 would have to be substituted for the one previously in use. If the gauge glass 68 is calibrated to indicate the pressure differential only, the rate of flow of oil in any installation can be readily 95 computed from the indicated differential and the known size of the orifice 34.

In actual installations which have been operated very successfully, an orifice 34 of one-quarter inch diameter and a pressure drop across the orifice of .65 pounds of oil have 100 been employed in firing a 250 horse power boiler at 125% of its rated capacity. In these installations the fuel oil used was Kansas crude having a specific gravity of about 34° 105 Baumé. The size of the orifice 34 is decreased in firing boilers of smaller capacity, but by using a low pressure differential, the size of the orifice for boilers of all capacities may be made large enough to permit all foreign solid 110 matter usually present in fuel oil to pass freely through it. In this connection it is to be noted that oils ordinarily used commercially for fuel purposes contain a considerable amount of solid matter which it is impractical 115 to remove from the oil by filtration or otherwise. Such matter usually consists of particles of dirt, etc. If the strainer 30 were designed to remove such particles from the oil, it would be quickly clogged by a large accumulation of matter. For this reason the strainer 120 30 is designed to remove from the oil only objects of considerable size. Such objects are not usually present in fuel oil, and the strainer may therefore be used for a long time without 125 cleaning.

The accuracy with which the rate of feed of oil to a burner can be controlled and regulated depends in great measure on the number of variable factors affecting the feed of 130

the oil. In the use of this invention, the number of such variable factors is reduced to a minimum. The size of the orifice 34 cannot be changed without substitution of one plate 32 for another. Such a substitution is generally not made after an installation is complete and cannot be made without interrupting the operation of the burner. Moreover, when one orifice plate is substituted for another, the substitution is not effected as a temporary adjustment but with a view to permanency, as, for example, when the capacity of the burner is changed. The status of the orifice 34 as a fixed rather than a variable factor in controlling the rate of flow of oil to the burner is further established by the fact that the orifice is always made of sufficient size so that it will interpose no obstruction to the passage through it of foreign solid matter such as is ordinarily present in fuel oil. This prevents solid matter from restricting either temporarily or permanently the actual size of the opening available for the passage of oil. As already indicated the rate of flow of oil through the orifice is entirely uninfluenced by change in the pressure on the oil in the pipe 28. The creation of a pressure drop across the orifice 34 involves two factors one of which, namely, the pressure on the delivery side of the orifice is substantially constant. Consequently, the only variable factor affecting the rate of flow of oil to the burner 14 is the pressure of the gaseous fluid on the oil in the trap 36. This invention not only enables the rate of flow of oil to the burner 14 to be controlled and regulated with great accuracy, but it also enables the rate of flow of oil to be very accurately determined by reference to the gauge glass 68.

Where a gaseous fluid under a pressure either greater or less than atmospheric pressure is conveniently available, it is preferred to utilize such fluid at one side of the orifice and atmospheric pressure on the other side of the orifice for producing and regulating the flow of oil through the orifice. It is recognized, however, that certain of the principles of the invention involving the use of a large orifice and a low-pressure drop across the orifice, can be applied in a commercial way with other means for inducing a drop in pressure across the orifice. For example, varying gaseous fluid pressures may be employed on both sides of the orifice, and when a gaseous fluid is not readily available the drop in pressure across the orifice may be varied by varying the head of the liquid oil on the orifice. In the latter event, however, the pressure of the oil at the orifice should be so controlled as to be independent of the pressure at which the oil is supplied to the flow-controlling mechanism.

The pressure of the gaseous fluid in the trap 36 may be varied manually or automatically within the scope of the invention. In the il-

lustrated construction, a mixture of steam and air is employed as the gaseous fluid and the pressure of the gaseous fluid is controlled automatically. To this end, steam is withdrawn from the boiler 10 by a conduit 70 including a pet-cock 72, valve 74, strainer 76, pressure regulator 78, pressure gauge 80, orifice nipple 82, and blow-cock 84. The steam is reduced to a pre-determined pressure by the pressure regulator 78, and its pressure is further reduced by passing through the orifice nipple 82. The conduit 70 communicates on the outlet side of the nipple 82 with a low pressure line 86 which transmits the gaseous fluid to the top of the stand-pipe 56, whence it is conducted to the trap 36 by the stand-pipe 56 and pipe 58.

It is contemplated that the stand-pipe 56 may be omitted from commercial installations. In such an event, the low pressure line 86 may be led directly to the trap 36, and the gauge glass 68 may be mounted on the trap 36.

The pressure regulator 78 is set to reduce the steam to the pressure best adapted for atomizing the oil in the burner 14, and a connecting pipe 88 leads from the conduit 70 intermediate between the pressure regulator 78 and the orifice nipple 82 to the burner. The pressure regulator 78 is of known construction and does not require detailed description. As seen in Fig. 6, steam passes through the regulator from left to right and is governed by a valve 90. The valve 90 is connected to a diaphragm 92, the under side of which is subjected to the pressure of the steam on the outlet side of the valve. If the pressure of the steam on the outlet side of the regulator tends to exceed that for which the regulator is set, the diaphragm 92 is forced upwardly against the tension of a spring 94 thus causing the valve 90 to move toward closed position. If, on the other hand, the pressure of the steam tends to fall below that for which the regulator is set, the spring 94 moves the valve 90 toward open position.

As hereinbefore indicated one of the features of the invention contemplates that the rate of flow of oil to the burner 14 shall be reduced whenever the pressure of the steam in the boiler tends to exceed a pre-determined degree. In carrying out this feature of the invention, the low pressure line 86 in the illustrated installation is provided with a pressure relief device 96 (Figs. 2 and 5) controlled by the pressure of the steam in the boiler. As shown, the device 96 is located at one end of the low pressure line 86 and comprises a casing formed to provide an inlet chamber 98 and an outlet chamber 100, the latter being open to the atmosphere. The flow of fluid through the device 96 is normally prevented by a valve 102 maintained in closed position by a lever 104 and weight 106.

106. The device 96 is formed at its upper end with a chamber 108 containing a diaphragm 110 connected to the valve 102. The chamber 108 above the diaphragm 110 is closed to the admission of air and has connected to it a pipe 112 leading from the conduit 70 on the inlet side of the pressure regulator 78. The pipe 112 conducts steam to the chamber 108 of the pressure relief device 96 substantially at boiler pressure. Consequently, if the pressure of the steam in the boiler tends to exceed that for which the device 96 is set, the valve 102 of the device is opened, thus relieving the pressure in the low pressure line 86 and reducing the feed of oil to the boiler.

The rate of supply of air for supporting the combustion of the oil fed to the boiler 10 is controlled by a damper 118 in the stack or flue 120 of the boiler in such a manner that whatever the rate of feed of oil to the boiler may be, air is admitted to the boiler in sufficient quantity to support the combustion of the oil but without any considerable excess. 25 As shown, the damper 118 is fixed on a rotatable shaft 122, provided at one end with a pulley 124 over which passes a cable 126. The cable 126 is attached at one end to a small weight 128 and at its other end to an actuator 20 arranged to move vertically in accordance with the pressure in the low pressure line 86. The actuator may have various forms. In the illustrated construction, however, it is in the form of an inverted bell 130 closed at its upper end and having its open lower end immersed in a sealing liquid contained in a tank 132. The pressure in the line 86 is transmitted to the bell 130 by a branch pipe 134 having its outer end extending upwardly 35 within the bell 130.

Fixed to the end of the shaft 122 opposite from the pulley 124 is a crank arm 136 carrying a weight 138. The length of the crank arm 136 is, preferably, equal to the radius of the pulley 124, and the arrangement of the damper 118, bell 130, and crank arm 136 is such that when the damper is closed, the bell 130 is in its lowermost position, and the crank arm 136 extends horizontally from the shaft 122 in a direction such as to cause the weight 138 to swing downwardly as the bell 130 is raised. From the foregoing it will be understood that the weight 138 tends in the closed position of the damper to raise the bell 130. 50 As the bell 130 is raised the moment of the weight 138 tending to lift the bell gradually decreases so that the gas pressure necessary to further elevate the bell increases as the bell attains the higher positions of its movement.

By reference to the well known equation for determining the rate of flow of liquid through an orifice, $Q = c a \sqrt{2gh}$, in which 65 Q represents the quantity or rate of flow, a ,

the area of the orifice, g , the gravity co-efficient, h , the pressure drop across the orifice and c , a co-efficient based on the shape of the orifice, it will be understood that the rate of flow of oil through the orifice 34 varies in accordance with the square root of the pressure in the low pressure line 86. 70

For convenience in explaining the principle of operation of the damper 118, the factors affecting the action of the damper may be 75 symbolized as follows:

W = the mass of the weight 138,

X = the net weight of the bell 130, that is, the weight of the bell minus the weight of the striker 142 and weight 128;

R = the moment arm of the bell 130 and weight 138 in inches;

a = the transverse area of the bell in square inches;

P = the gas pressure in the bell in inches of water;

A = the transverse area of the stack 120 at the damper;

D = the area of the damper; and

ϕ = the angle made by the arm 136 and the damper 118 with the horizontal plane through the damper axis. 90

The moments of the weight 138 and the bell 130 when the arm 136 is in horizontal position and the damper 118 closed are usually made substantially equal so that when there is atmospheric pressure only in the bell 130, the weight 138, damper 118, and bell 130 are in equilibrium. Accordingly $WR = X R$, and when the length of the arm 136 equals the radius of the wheel 124, W and X are also made substantially equal. 95

One cubic inch of water weighs .036127 lbs. Accordingly, for any position of the damper 118 between wide open and closed positions, 100

$$WR \cos \phi = X R - .036127 a P R \text{ or}$$

$$\cos \phi = \frac{X - .036127 a P}{W}$$

The projected area of the damper 118 will equal $D \cos \phi$ and the area of the damper opening will be $A - D \cos \phi$. 110

Substituting the value of $\cos \phi$ in the last mentioned equation the area of the damper opening is ascertained to be equal to 115

$$A - D \left\{ \frac{X - .036127 a P}{W} \right\}.$$

In this equation A , D and a are fixed at the time an installation is made, and x and W are constants in any particular setting of the damper, although they may be varied to adjust the damper to suit operating conditions. The operating variables in the above equation are the area of the damper opening and the pressure in the bell 130 denoted by P . Consequently, there is a direct proportion between the area of the damper opening and the pressure in the bell 130. 120 125 130

Experiments appear to indicate that the rate of flow of air through the boiler 10 varies substantially in direct proportion to the area of the opening defined by the stack damper, and that the amount of air supplied to the furnaces will be properly proportioned to the rate of feed of the oil, when the area of the damper opening varies in about the same ratio as the rate of feed of oil to the boiler furnace.

When the damper 118 is moved from closed position a comparatively large angular movement of the damper produces only a small increase in area of the damper opening. Consequently, if the damper 118 were caused to move angularly in direct proportion to the pressure in the bell 130, the boiler would be properly ventilated only when the pressure in the bell 130 approximated the maximum pressure required to cause the damper 118 to be fully opened. At all lower pressures the boiler would be badly under-ventilated. By causing the area of the damper opening to vary in proportion to the pressure in the bell 130, the rate of flow of air through the boiler furnace is caused to vary in a ratio which quite closely approximates the variations in the rate of flow of oil to the burner 14.

It is never desirable that a stack damper be made to fit a stack tightly because of the danger of the accumulation of explosive gases. In the use of this invention the existence of a considerable area of leakage between the damper 118 when in closed position and the stack causes the ratios of the ventilation and the rate of flow of oil to approach each other more closely than if there were no leakage. If the leakage area about the damper 118 when in closed position is 25% of the transverse area of the stack at the damper, and the installation is set to attain maximum combustion capacity at a pressure of 18 inches of water, the ventilation of the boiler 10 would be theoretically correct at 33% of combustion capacity and a pressure of 2 inches of water and also at full combustion capacity. Between 33% and 100% of combustion capacity, the boiler in case only the area of the orifice, the head of oil across the orifice, and the area of the opening defined by the stack damper are considered would theoretically be slightly under-ventilated. It has been found, however, by experience that the boiler under such conditions is actually slightly over-ventilated, due it is thought, to the effect of increasing flue-gas temperature with increased rates of combustion and also to the fact that the law of flow of gases past the stack damper is not exactly the same as the law governing flow of fluids through an "orifice in thin plate."

It has been determined in a number of commercial installations that by the use of this invention, the ventilation of a burner may be accurately proportioned to the rate of

feed of oil to the burner, as evidenced by a constant percentage of CO_2 in the exhaust gases, between combustion rates of 25% and 100%. It is not ordinarily of commercial importance to regulate the ventilation of a burner in strict accordance with the rate of flow of oil to the burner at rates of combustion less than 25% of maximum.

In actual practice the weight 138 and the weight of the bell 130 in excess of the weight 128 are made large enough so that the maximum allowed pressure in bell 130 is insufficient to open the damper completely. Inasmuch as the moment of the weight 138 is decreased as the bell 130 is raised, the degree of angular opening of the damper for a given maximum pressure can be decreased by merely adding equal weights to the weight 138 and the bell 130. In this way the maximum degree of opening of the damper 118 may be made greater or less according as the draft intensity which governs the velocity of flow of gases through the stack is small or large. This adjustment to compensate for varying draft intensities is made possible by the fact that the area of the damper opening is automatically kept in direct proportion to the pressure in the bell 130 irrespective of the weight of the parts 138 and 130. It is contemplated, however, that, in the use of the invention, the draft intensity will also be regulated in the usual manner as, for example, by secondary dampers or openings at the inlet to the boiler furnace.

If the boiler 10 were operated at a heavy load it would be possible for oil to be fed to the burner 14 in excess of the safe combustion capacity of the boiler without generating sufficient pressure in the boiler to operate the relief device 96. It is desirable that the rate of flow of oil to the burner shall be limited to the safe combustion capacity of the boiler regardless of the load on the boiler. To this end the low pressure line 86 is provided with an upstanding portion 139 which is open to the atmosphere. The flow of fluid through the portion 139 is controlled by a butterfly valve 140 which is normally closed, but is arranged to be opened whenever the pressure in the low pressure line 86 tends to exceed a pre-determined maximum. Manifestly, since the rate of flow of the oil depends on the pressure in the line 86, the relief of such pressure at a pre-determined maximum degree limits the rate of flow of oil to the boiler furnace.

In order to relieve the pressure in the low pressure line 86 when the rate of feed of the oil tends to exceed the maximum rate desired, the valve 140 in the upstanding portion 139 of the pressure line 86 is operatively connected to a lever 141 having an opening in one end through which the cable 126 passes. The cable 126 carries a weight or striker 142 positioned so as to engage the end of the lever 130

141 and thereby open the valve 140 when the damper 118 attains the most widely opened position for which it is adjusted. The striker 142 may be located in various positions on the cable 126 in accordance as the maximum degree of opening of the damper 118 is changed. The valve 140 is returned to closed position by a weighted plunger 144 connected to the other end of the lever 141. The plunger 144 is preferably enclosed in a dash-pot so as to dampen the movements of the valve 140. The weight 128 is of a size sufficient only to properly control the cable 126 and striker 142.

15 The flow of steam through the nipple 82 induces flow of air into the low pressure line 86 through the aspirator 84. The air reduces the amount of steam required to be supplied to the line 86 not only directly by taking the place of steam that would otherwise be required to produce the necessary pressure but also indirectly by reducing condensation of the steam in the low pressure line 86, oil trap 36, and bell 130. The reduction in the condensation of the steam arises from the fact that a mixture of steam and air has a much lower temperature than pure steam at the same pressure.

20 The low pressure line 86 is preferably provided at its low point with a pet-cock 146 (Fig. 2) which is left open continuously to allow the escape of water formed by condensation of steam in the line. The amount of steam and air which issues from the pet-cock is negligible. The pet-cock 72 may be opened to permit the escape of water from the high pressure conduit 70.

25 It is first decided what the maximum gaseous fluid pressure on the oil in the trap 36 shall be. Then the mass of the weight 138 and the net weight of the bell 130 are calculated from the equation

$$\cos \phi = \frac{x - 036127 aP}{W}$$

30 In this computation X and W are assumed to be equal and they are so calculated as to cause the damper to be opened at an angle of 75 or 80 degrees to the horizontal at the maximum burner pressure. The cross-sectional area of the bell, denoted by a , in commercial installations is about 60 square inches.

35 Although in the above calculations the weights X and W have been assumed to be equal, it is recognized that the net weight of the bell 130, denoted by X, may be made somewhat greater than the weight W without departing from the principles of the invention. In fact, in some installations as, for example, in cases where the area of the stack damper is considerably less than the transverse area of the stack, it is advantageous to make the weight X slightly in excess of the weight W. The weight X can be varied by adding or removing weights from the bell 130. The ef-

fect of making the weight X greater than the weight W is to cause the opening of the damper to be delayed with respect to the development of pressure in the oil trap 36 and the low pressure line 86 and to cause the damper to close a short time before the pressure in the bell 130 is reduced to atmospheric. The weight of the bell 130 is sufficiently close to the weight 138 to enable the weights X and W to be calculated from the above equation with sufficient accuracy to satisfy all practical requirements.

40 In the use of the illustrated apparatus, assuming the boiler 10 to be cold, the valve 55 in the pilot pipe 54 is first opened to allow oil to flow to the burner 14. When steam has been generated in the boiler, the valve 55 is nearly or fully closed, and the valve 74 in the conduit 70 is opened to allow steam to pass into the low pressure line 86. The pressure regulator 78 is set to cause steam to be delivered from it at a desired pressure which is indicated by the gauge 80. The pressure of the steam is further reduced by the orifice nipple 82 and air is admitted through the aspirator 84 to form a mixture of steam and air. Steam at the pressure determined by the pressure regulator 78 is conducted to the burner 14 to atomize the oil, and the size of the orifice in the nipple 82 is so proportioned to the pressure of the steam as it issues from the regulator 78 that the mixture of steam and air in the low pressure pipe 86 may develop a pressure greater than that necessary to cause oil to be fed at the maximum rate. The pressure which may be developed in the low pressure pipe 86 is, however, limited by the size of the orifice in the nipple 82 to a degree such that it may quickly be reduced to the required extent in the event that the steam pressure in the boiler tends to become excessive or the pressure in the low pressure line 86 tends to exceed that necessary to cause oil to be fed to the burner at the desired maximum rate. The valve 102 of the pressure relief device 96 is operated to reduce the pressure in the low pressure line quickly in case the pressure of the steam in the boiler tends to exceed the degree determined by the relief device. The striker 142 on the cable 126, is, however, generally moved very slowly in response to like movements of the bell 130. Consequently, the valve 140 is not moved abruptly but is gently urged toward open position by the weight of the striker resting on the lever 141. The plunger 144, and the dash-pot also tends to impart a gentle action to the valve 140. The result of the above described action of the valve 140 is to cause the conditions which control the operation of the boiler to be maintained substantially constant when the boiler is being operated at or near the full capacity of the burner 14.

45 The operation of the boiler may be quickly discontinued by closing either the valve 74

in the high pressure conduit 70 or the valve 29 in the oil supply pipe 28 or both. When the operation of the boiler is stopped by closing the valve 74, the pressure of the steam and air in the low pressure line 86 and oil trap 36 is quickly relieved by the emission of steam and air through the aspirator 84. Inasmuch as the pressure in the line 86 is always very small, the relief of the pressure when

the valve 74 is closed is practically instantaneous. In case the operation of a field boiler is stopped and the boiler moved to a different location, the valve 29 should be closed to prevent accidental flow of oil in the oil feed line.

Having fully described the invention what is claimed is:

1. In an apparatus of the class described, a boiler furnace, and means for feeding oil to a burner in the furnace comprising an oil containing chamber, a member on the delivery side of the chamber provided with an orifice through which the oil is fed, means for maintaining the outlet side of the orifice under atmospheric pressure, means for producing a superatmospheric pressure in said oil chamber to feed oil through the orifice, means for maintaining the oil in the oil chamber constantly at the level of the orifice, and a direct gravity run between said

orifice and said burner.

2. In an apparatus of the class described, a boiler, an oil burner for heating said boiler, and means for feeding oil to said burner comprising a supply chamber, connections between said chamber and said burner including a restricted opening of uniform area, connections between said boiler and said chamber including a reducing valve, a restricted opening of constant area intermediate said reducing valve and said chamber, and means for automatically venting the pressure in said second mentioned connection and chamber.

3. In an apparatus of the class described, a field boiler, a furnace for the boiler provided with a burner, and means for feeding oil to the burner comprising a member provided with an orifice through which the oil is fed, an oil containing chamber on the supply side of the orifice, means for maintaining the oil in the chamber substantially at the level of the orifice, means for subjecting the delivery side of the orifice to atmospheric pressure, and means for imposing a gaseous fluid pressure slightly greater than atmos-

pheric on the oil in said chamber to produce flow of oil through the orifice, said orifice being of sufficiently large size so as to enable an adequate supply of fuel oil to be delivered to said boiler with a gaseous fluid pressure in said chamber of 30 inches of oil so that oil may be fed by gravity from a field tank to the chamber.

4. In an apparatus of the class described, an oil burner, and means for feeding oil to the burner comprising an oil trap, a hollow

member associated with the trap, an orifice plate arranged to communicate on its supply side with the hollow member, a chamber communicating with said plate on its delivery side, means for exerting pressure not substantially exceeding one pound per square inch on the oil in the trap, and means for conducting oil under atmospheric pressure from the delivery side of the orifice to the burner.

5. In an apparatus of the class described, an oil burner, and means for feeding oil to the burner comprising an oil trap, means for maintaining the oil in the trap at a predetermined level, a pipe communicating with the trap below the level of the liquid in the trap and extending upwardly, a chamber enclosing the upper end of the pipe and open to the atmosphere, an orifice plate mounted in substantially the same horizontal plane as the level of liquid in the trap and arranged to communicate on its supply side with the pipe and on its delivery side with the chamber, means for conducting oil by gravity from the delivery side of the orifice to the burner, and means for imposing gaseous pressure greater than atmospheric on the oil in the trap to produce flow of oil to the burner.

6. In an apparatus of the class described, a boiler, means for feeding oil to the furnace of said boiler, mechanism for controlling the ventilation of the furnace, a fluid pressure line for controlling the feed of the oil to the furnace and for operating said mechanism, means for conducting steam from the boiler to the fluid pressure line, and a pressure regulator and a constant area orifice member for controlling the passage of steam from the boiler to the pressure line.

7. In an apparatus of the class described, a boiler, means for feeding oil to the furnace of said boiler, mechanism for controlling the ventilation of the furnace, a fluid pressure line for controlling the feed of oil to the furnace and for operating said mechanism, a pipe for conducting steam from the boiler to the pressure line, and an aspirator in said pipe for causing air to be drawn into the pipe in order to dilute the steam and thus reduce condensation of steam in the feeding means and in said mechanism.

8. In an apparatus of the class described, a boiler, means for feeding oil to the furnace of said boiler comprising a member provided with an orifice, a conduit for conducting steam from the boiler to the feeding means on the supply side of the orifice so as to impose greater pressure on the oil at the supply side of the orifice than on the delivery side to induce flow of oil to the furnace, a valve in said conduit for shutting off the supply of steam to the feeding means, and an aspirator in said conduit on the outlet side of the valve, said aspirator being constructed to cause air

to be drawn into said conduit by flow of steam through the conduit when the valve is open and to permit flow of air and steam outwardly from the conduit when the valve is closed so as quickly to reduce the pressure in the feeding means to atmospheric.

9. In an apparatus of the class described, a boiler, means for feeding oil to the furnace of said boiler, mechanism for controlling the ventilation of the furnace, a line of piping for conducting steam from the boiler, a pressure regulator in said piping, an orifice member on the outlet side of the regulator, a connection between the piping and the furnace for conducting steam to the furnace to atomize the oil, said connection communicating with the piping between the pressure regulator and the orifice member, and means connected with the piping on the outlet side of the orifice member for transmitting steam at low pressure to the feeding means and said mechanism.

10. In an apparatus of the class described, a boiler, means for feeding oil to the furnace of said boiler, a line of piping for conducting steam from the boiler, a pressure regulator in said piping, an orifice member on the outlet side of the regulator, a connection between the piping and the furnace for conducting steam to the furnace to atomize the oil, said connection communicating with the piping between the pressure regulator and the orifice member, and a connection between the piping on the outlet side of the orifice member and the feeding means for transmitting steam at low pressure to the feeding means.

11. The method of controlling combustion in oil-fired boiler furnaces which consists in withdrawing steam from the boiler, reducing the steam to a pre-determined pressure, utilizing steam at such pressure for atomizing the oil in the boiler furnace, reducing the steam to a still lower pressure, and utilizing steam at the last-mentioned pressure for controlling the feed of oil to the furnace.

12. The method of controlling combustion in a furnace for which oil is atomized by a fluid which consists in supplying the atomizing fluid at a constant pressure, and utilizing a portion of the atomizing fluid at a varying pressure lower than the atomizing pressure for controlling the feed of oil to the burner.

13. The method of controlling combustion in oil-fired boiler furnaces which consists in withdrawing steam from the boiler, reducing the steam to a pre-determined pressure, utilizing the steam at such pressure for atomizing the oil in the furnace, further reducing the pressure of the steam, and utilizing the steam at the last-mentioned pressure for controlling the ventilation of the furnace.

14. The method of controlling combustion in oil-fired boilers which consists in withdrawing steam from the boiler, reducing the steam to a pre-determined pressure, utilizing

steam at such pressure for atomizing the oil, further reducing the pressure of the steam, utilizing the steam at the last-mentioned pressure for controlling the ventilation of the boiler and the feed of the oil, and utilizing steam from the boiler at a pressure varying in accordance with the boiler pressure for reducing flow of the oil to the boiler when the pressure of the steam in the boiler tends to exceed a pre-determined amount.

15. The method of controlling combustion in oil fired boilers which consists in withdrawing steam from the boiler, reducing the steam to a predetermined low pressure which remains substantially constant regardless of changes in pressure of the steam in the boiler, utilizing a still lower fluid pressure derived from said constant pressure for controlling feed of oil to the boiler furnace, and releasing the oil feed control pressure whenever the pressure of the steam in the boiler tends to increase beyond a predetermined amount.

16. A method of controlling combustion in boiler furnaces comprising establishing a stream of elastic fluid flowing continuously during periods of normal steam pressure in the boiler to be controlled, developing a relatively low super-atmospheric pressure by means of said stream and utilizing such pressure to control the flow of fuel to the boiler furnace, and governing the rate of flow of fuel to the furnace by gradually opening said stream to the atmosphere to a greater or less extent in accordance with variations of the steam pressure of the boiler.

17. In an apparatus of the class described, a boiler, pressure controlled means for feeding oil to the furnace of the boiler, means for conducting steam from the boiler to the feeding means and separate means for relieving the pressure of the steam in the feeding means both when the oil feed tends to exceed a predetermined maximum and when the pressure of the steam in the boiler tends to exceed a predetermined amount.

In testimony whereof I affix my signature.

BENJAMIN GREENFIELD.
